UNITED STATES PATENT OFFICE

CHARLES R. EVERSON, OF MACEDON, NEW YORK, ASSIGNOR TO LEONARD L. CRAMER, OF SAME PLACE.

SOLDER-HOLDER.

SPECIFICATION forming part of Letters Patent No. 303,219, dated August 5, 1884.

Application filed December 8, 1883. (No model.)

To all whom it may concern:

Be it known that I, CHARLES R. EVERSON, a citizen of the United States, and a resident of Macedon, Wayne county, New York, have invented certain new and useful Improvements in Solder-Holders, of which the following is a specification.

My invention is a device constructed as fully described hereinafter, whereby to hold small pieces of solder which cannot be manipulated in connection with the soldering-iron when held directly in the hand, thereby avoiding the loss incurred by the non-use or remelting and recasting of such pieces.

15 In the drawing is shown a perspective view of my improved solder-holder.

The implement consists of a shank, A, formed at one end into a handle, B, and having at the other end a clamp for securing the 20 small pieces X of solder which it is desired to hold. The clamp consists of a finger, a, projecting from the shank, and a screw, b, which passes through a second finger, c, and between which and the finger a the solder is firmly 25 clamped. It will be seen that one of the fin-

gers, c, projects beyond the other. This is important as the ends of the pieces are often rounded or beveled and could only be held between jaws of equal length by introducing a considerable portion back of the gripping points, which portion could not be used, while by the construction described almost the entire piece can be utilized. The handle is tapered at its end and formed with a flat edge substantially like a screw-driver. By this 35 construction the workman can press down or open the seams before soldering.

I claim—

The shank A, formed at one end into a tapered flat edge and at the other having the 40 projecting fingers a c, the finger c being longer than the other and provided with a clamping-screw, as set forth.

In testimony whereof I have signed my name to this specification in the presence of two sub- 45 scribing witnesses.

CHARLES R. EVERSON.
